(57) **CLAIM**

The ornamental design of a cap for a container, as shown and described.

DESCRIPTION

FIG. 1 is a side elevation view of the cap of the present invention.

FIG. 2 is a front elevation view of the cap depicted in FIG. 1.

FIG. 3 is a top plan view of the cap depicted in FIG. 1. FIG. 4 is a bottom plan view of the cap depicted in FIG. 1; and,

FIG. 5 is a top side perspective view of the cap depicted in FIG. 1.

The height of the upper portion of my design is variable.
